[57] **CLAIM**

The ornamental design for a synthetic foam chair cushion, as shown and described.

DESCRIPTION

FIG. 1 is a front side perspective view of a synthetic foam chair cushion, showing our new design;

FIG. 2 is a top end elevational view thereof, the bottom end being substantially identical;

FIG. 3 is an enlarged detail view, showing the uniform peak geometry of the convoluted surface thereof;

FIG. 4 is a side elevational view thereof, the opposite side being substantially identical; and,

FIG. 5 is a front plan view thereof.

The convoluted foam surface is fragmentarily shown in FIGS. 1, 2 and 5 for ease of illustration and is understood to extend throughout the area represented.
